GAME ACCESSORY FOR USE WITH SPINNING TOYS

Anthony D. Miller, Torrance, and John T. Benson, Los Angeles, Calif., assignors to Mattel, Inc., Hawthorne, Calif.

Filed July 23, 1970, Ser. No. 24,080

Term of patent 14 years

Int. Cl. D21—01

U.S. Cl. D34—15

FIG. 1

FIG. 2

FIG. 3

FIG. 4

FIG. 5

FIG. 6

FIG. 7

FIG. 8

FIG. 1 is a top perspective view of a game accessory for use with spinning toys embodying our design;

FIG. 2 is a top view thereof;

FIG. 3 is a front edge view thereof;

FIG. 4 is a side sectional view taken generally along the lines 4—4 of FIG. 3;

FIG. 5 is a rear view of same;

FIG. 6 is a right side view thereof;

FIG. 7 is a left side view thereof; and

FIG. 8 is a bottom view.

We claim:

The ornamental design for a game accessory for use with spinning toys, as shown.
